UNITED STATES PATENT OFFICE

2,046,441

CLOSURE OPERATOR

Ervin Fred Arndt, Tinley Park, Ill.

Application June 7, 1935, Serial No. 25,508

2 Claims. (Cl. 268—41)

This invention relates to the class of closure operators and an object of the invention is to provide efficient means whereby a door may be moved to an open position through the medium of suitable mechanism upon the depressing of a treadle or platform arranged at either or both sides of the door.

A further object of the invention is to provide an improved door operating mechanism applicable for use in conjunction with garage doors, doors of any suitable type of building or for operating the door or gate forming part of an enclosure for live stock or poultry. Further it is an object of the invention to provide a door operating mechanism of such simple construction, and economy of parts, that the same may be used for operating the door of a game trap or of a cage for birds or animals.

The invention together with its objects and advantages will be best understood from a study of the following description taken in connection with the accompanying drawings wherein:

Figure 1 is a view for the most part in elevation illustrating the application of the invention and showing the parts in open position.

Figure 2 is a view similar to Figure 1 with the door in closed position.

Figure 3 is a vertical detailed sectional view taken at right angles to Figure 2 and illustrating certain details hereinafter more fully referred to.

Figure 4 is a longitudinal sectional view through the platform.

Figure 5 is a view showing in top plan view the structure shown in Figure 4.

Referring to the drawings by reference numerals it will be seen that 5 indicates generally a front wall structure provided with a doorway or opening 6, and at one side of the doorway 6 the wall is hollow to accommodate a door 7 when the latter is in open position.

The door 7 is of the sliding type and is suspended by brackets 8 equipped with rollers 9 slideable on a rail 10 that extends across the top of the doorway 6 as shown.

Suitably and pivotally mounted within the wall 5 a suitable distance away from the doorway 6 and as indicated generally at 11 is a substantially L-shaped link 12 which at one end is pivotally connected through the medium of a link 13 with an upper corner of the door 7 as shown in Figure 1. The other and shorter arm of the lever 12 is pivotally connected through the medium of a link 14 with a second link 15 pivotally mounted within the wall as at 16. The link 15 in turn is connected by a link 16 with a treadle

bar 17 pivotally mounted at 18 adjacent one side of a runway indicated generally by the reference numeral 19.

In the present instance the runway 19 extends through the doorway 6 from the outer side to the interior of the building and is in the form of an elongated trough through one side of which extends and operates the treadle 17.

Pivotedly mounted between the sides of the trough of the runway, in the present instance both interiorly and exteriorly of the building are platforms 20. The platforms 20 are pivoted at the ends thereof nearest to the doorway by rods 21. The platforms 20 are normally retained in a substantially level condition through the medium of pairs of spaced springs 22 suitably anchored at their lower ends to the bottom of the trough of the runway and suitably connected at their upper ends to an angle bar 23 secured to the underside of a platform and extending transversely thereof as best shown in Figures 4 and 5.

Secured to an intermediate portion of each of the angle bars 23 is a rocker arm 24 pivoted within the trough of the runway through the medium of a rod 25. The ends of the treadle bar terminating within the trough of the runway 19 is forked to provide divergently extending arms 17a engaging the free ends of the arms 24 as shown in Figures 4 and 5.

For normally urging the door 7 to a closed position is a spring 26 anchored at one end immediately adjacent the doorway 6 and at its opposite end secured to an intermediate portion of an arm of the lever 12 as best shown in Figures 1 and 2. The spring 26 normally urges the lever 12 to swing in a clockwise direction for moving the door 7 to a closed position across the doorway 6.

In actual practice it will be seen that to open the door the weight of a person or a vehicle on a platform 20 will tend to depress the platform. The depressing of the platform will cause a swinging movement of the associated lever 24 in a clockwise direction, and this movement is transmitted to the treadle bar 17 forcing the latter to swing in a counter clockwise direction. Movement of the treadle bar 17 in this direction is transmitted through the links 16, 15 and 14 to the lever 12 causing the latter to swing in a counter-clockwise direction against the action of spring 26 resulting in a sliding of the door from the closed position shown in Figure 2 to the open position shown in Figure 1. Obviously when the weight is removed from the depressed

platform, the latter under action of springs 22 will swing upwardly to a substantially level position causing a reversal of the operation just described and resulting in a sliding movement of the door 7 to a closed position across the doorway 6.

To secure the platform 20 against being depressed an amount sufficient and required to operate the door 7 when the latter is in closed position, there is provided a suitable mechanism consisting of a shaft 27 rockably mounted transversely of the trough of the runway as shown in Figures 4 and 5. Provided on the shaft 27 at spaced points are stop arms or abutments 27a that are adapted to be swung upwardly to a vertical position to limit downward movement of the platform 20 in response to a weight thereon and thereby prevent an opening of the closed door 7. For operating the shaft 27 there is provided at one side of the runway, a pivotally mounted lever 28 connected through the medium of link 29 with a crank arm 30 provided on one end of the shaft 27. Obviously any suitable means, (not shown) may be employed for securing the lever 28 at the desired adjustment for retaining the abutment arms or stops 27a in either the vertical position for limiting downward movement of the platform 20 or in the horizontal position shown in Figure 4 to permit free depressing movement of the platform.

While I have shown the use of two platforms, one internally and one externally of the building, it will be understood that where desired but a single platform may be used as for example, when the mechanism is made use of for operating the door of an animal enclosure, a trap, or other suitable structure or enclosure.

Having thus described the invention, what is claimed as new is:

1. In a closure operator, the combination with a sliding door, an L-shaped pivotally mounted lever, link means connecting the free end of the longer arm of said L-shaped lever with an upper corner of the door for transmitting movement of the lever to the door for moving the latter to

either an opened or closed position optionally, a pivotally mounted treadle bar, a pivotally mounted arm, link means connecting each free end of the arm with the free end of the L-shaped lever and the treadle bar, a pivotally mounted platform, a vertically disposed coil spring resiliently supporting the free end of the platform, and being disposed beneath said platform, a pivotally mounted arm beneath said platform, one end of said arm being disposed between the upper end of the coil spring and the lower side of the platform, the other end of said arm, co-operating with the treadle for actuating the same.

2. In a closure operator, the combination with a sliding door, an L-shaped pivotally mounted lever, link means connecting the free end of the longer arm of said L-shaped lever with an upper corner of the door for transmitting movement of the lever to the door for moving the latter to either an opened or closed position optionally, a pivotally mounted treadle bar, a pivotally mounted arm, link means connecting each free end of the arm with the free end of the L-shaped lever and the treadle bar, a pivotally mounted platform, a vertically disposed coil spring resiliently supporting the free end of the platform, and being disposed beneath said platform, a pivotally mounted arm beneath said platform, one end of said arm being disposed between the upper end of the coil spring and the lower side of the platform, the other end of said arm, co-operating with the treadle for actuating the same, and a horizontally disposed rotatably mounted shaft beneath the free end of said platform, having laterally extending arms adapted in a vertical position to abut the underside of the platform to prevent the same from being moved to a lowered position, a link connected to said shaft, and means for operating said link to move the arm to an operative or an inoperative position with respect to the platform to prevent the lowering of the same.

ERVIN FRED ARNDT. 45
